UNITED STATES PATENT OFFICE.

SIDNEY P. DODGE, OF WEST UNITY, OHIO.

HAT HANGER AND MARKER.

No. 885,026.

Specification of Letters Patent. Patented April 21, 1908.

Application filed March 18, 1907. Serial No. 368,032.

To all whom it may concern:

Be it known that I, SIDNEY P. DODGE, a citizen of the United States, residing at West Unity, in the county of Williams and State 5 of Ohio, have invented certain new and useful Improvements in Hat Hangers and Markers, of which the following is a specification, reference being had therein to the accompanying drawing.

10 My invention relates to improvements in devices for hanging hats or the like upon a rack or other support.

One object of the invention is to provide a simple and inexpensive hanger of this character which may be conveniently carried in one's pocket and readily attached to one's hat so that it may be conveniently hung upon any sort of rack in such manner that there will be little or no danger of it being knocked 20 off.

Another object of the invention is to provide a hanger of this character which may be engaged with the buttonhole in the lapel of an overcoat or with a buttonhole in any other 25 garment.

A further object of the invention is to provide a device of this character with means for displaying the name and address of the owner or any other distinguishing mark by 30 means of which it may be identified and the owner may readily locate his hat, coat or other belongings placed in the cloak rooms of hotels or other public places.

With the above and other objects in view 35 the invention consists in the novel features of construction, combination and arrangement of parts hereinafter described and claimed, and illustrated in the accompanying drawings, in which

40 Figure 1 is a view showing two uses of my improved hanging and marking device; Fig. 2 is a front elevation of the device on an enlarged scale; and Figs. 3 and 4 are sectional views taken respectively on the planes indicated by the lines 3—3 and 4—4 in Fig. 2.

The invention consists of a clasp 1, a suspending ring or loop 2 and an attaching and marking button 3. The clasp 1 is here shown as consisting of a bottom member 4 formed of sheet metal and having at one of its ends a flat jaw 5 and its other end 7 bent around a flattened portion 8 of the ring or loop 2 which latter is of substantially circular form. Intermediate the ends of the member 50 or plate 4 are formed at its opposite sides apertured bearing ears 9 which are bent up

at right angles and are adapted to register with similar ears 10 similarly arranged upon the top or outer member 11 of the clasp. This member is also preferably formed of a piece of sheet metal and has a finger piece 12 at one end and its other end curved, as shown in Fig. 3, to provide a flat jaw 13 which coacts with the jaw 5. These jaws are pressed together and upon the hat or other article inserted between them by a coil spring 14 which surrounds a pivot pin 15 passed through the alining apertures in the bearing ears 9, 10, said spring having its ends bearing against the inner faces of the members 4, 11, 60 as shown in Fig. 3. The provision of the flat jaws 5, 13 permit them to readily engage the rim of a hat and the curvature of the jaw 13 provides sufficient space between the inner portions of said jaws for the reception of the bead upon the rim of a derby and hence causes the clasp to more effectively hold such a hat, as will be readily understood. The button 3 not only serves as a means which permits the article to be attached to a garment by inserting such button in a button-hole, but also serves as an identifying or marking tag. Said button or device 3 comprises a back plate 16 of circular shape formed with an annular bead or rim 17 and 70 with an integral centrally disposed and rearwardly projecting shank 18 transversely apertured to receive the ring 2, as clearly shown in Fig. 3. The back plate 16 forms a chamber for the reception of a disk 19 of 80 paper or other suitable material upon which may be printed, written, or otherwise marked, the name and address of the owner of the device, or any other desired information. The disk 19 is preferably covered by a 85 disk 20 of celluloid or other transparent material which will protect the disk 19. These disks are retained upon the back plate by a front plate or rim 21 having a central opening to expose the disks or plates 19, 20 and 90 having an annular rim or flange 22 to engage the rim or flange 17 of the back plate. The parts 16, 21 may be held together by the frictional engagement of the flanges 17, 22, or 95 any other suitable detachable connection 100 may be provided.

While the invention may be used in various ways and for suspending various objects or articles, the two uses for which it is especially designed are illustrated in Fig. 1 in 110 which it will be seen that the clasp 13 is engaged with the rim of a derby H and in one

2
case the button 3 is inserted in the button-hole of the lapel in a coat C and in the other case, said button is swung downwardly upon the lower portion of the ring 2 and the latter 5 is engaged with one of the hooks of the rack R. The device is of such size that it may be conveniently carried in the pocket of one's vest and it is so constructed that it may be readily attached to a hat or other article and 10 suspended from a hook or support of almost any description. The provision of the identifying tag or button enables the owner to readily locate his hat, or the like, in public places so that there is little or no danger of 15 him getting the wrong hat.

Having thus described my invention what I claim and desire to secure by Letters Patent is:—

A hanger and marker of the character de-

scribed comprising a ring adapted to be engaged with a suspending device, a spring clasp pivoted upon said ring and an identifying button adapted to be engaged with the button hole of a garment to suspend the device and the object engaged by the clasp, 25 said button having an apertured shank to loosely receive said ring thus allowing the button to be swung about the ring and also to be moved circumferentially to use either the ring or the button as the supporting 30 means.

In testimony whereof I hereunto affix my signature in presence of two witnesses.

SIDNEY P. DODGE.
